UNITED STATES PATENT OFFICE.

GUSTAV HOFFMAN, OF YONKERS, NEW YORK.

DESIGN FOR A KETTLE OR POT SCRAPER.

SPECIFICATION forming part of Design No. 34,272, dated March 26, 1901.

Application filed March 1, 1901. Serial No. 49,518. Term of patent 7 years.

To all whom it may concern.

Be it known that I, GUSTAV HOFFMAN, a citizen of the United States, and a resident of Yonkers, in the county of Westchester and State of New York, have invented and produced a new and original Design for a Kettle or Pot Scraper, of which the following is a full, clear, and exact description.

Reference is to be had to the accompanying drawings, forming a part of this specification, in which similar characters of reference indicate corresponding parts in both the figures.

Figure 1 is a plan view of a kettle or pot scraper, showing my design; and Fig. 2 is an edge view of the same.

The leading feature of my design for a kettle or pot scraper consists in the plate-like body, one edge of which is formed in an outwardly-curved line, one end forming a point with the opposite edge, a portion of said opposite edge being on a straight line divergent from the curved edge, and another portion of said opposite edge being curved inward and connecting with the outwardly-curved edge

by a projection rounded at the end and opposite the pointed end.

Referring particularly to the drawings, the body 1 is shown with a rectangular opening 2, and one edge 3 of the body portion is curved outwardly and connects at one end and forms 30 a point 4, with an opposite straight edge 5, divergent from the point and connecting with an inwardly-curved edge 6, which connects with the curved edge 3 by a projection 7, rounded at its end.

Having thus described my invention, I claim as new and desire to secure by Letters Patent—

The design for a kettle or pot scraper, as herein shown and described.

In testimony whereof I have signed my name to this specification in the presence of two subscribing witnesses.

GUSTAV HOFFMAN.
